UNITED STATES PATENT OFFICE.

WESLEY S. MALLOY, OF OAKLAND, AND RAY J. LYMAN, OF BERKELEY, CALIFORNIA.

HYDRAULIC BORING DEVICE.

Application filed October 22, 1924. Serial No. 745,122.

Our invention relates to a hydraulic device for boring a hole through hard packed earth, or the like.

An object of the invention is to provide a device of the character described which is particularly adapted to have the fluid flow therefrom controlled at the nozzle thereof.

Another object of the invention is to provide a device of the character described in which control of the fluid flow may be effected by pressure of the device against the material to be removed.

The invention possesses other objects and features of advantage, some of which, with the foregoing, will be set forth in the following description of the preferred form of our invention which is illustrated in the drawings accompanying and forming part of the specification. It is to be understood that we do not limit ourselves to the showing made by the said drawings and description, as we may adopt variations of the preferred form within the scope of our invention as set forth in the claims.

25 Referring to said drawings:—

Figure 1 is an assembly view partly in section showing one embodiment of the device operatively attached to a source of liquid.

30 Figure 2 is an enlarged sectional view of a portion of the embodiment shown in Figure 1 showing the nozzle and its mounting.

Figure 3 is a sectional view showing another embodiment of the nozzle, its mounting, and a control valve for the former.

35 Figure 4 is a sectional view showing still another modified form of the nozzle and its mounting provided with a manually operable control valve.

40 Figures 5 and 6 are sectional views showing modifications of the embodiment shown in Figure 3.

Briefly expressed, the device of our invention comprises a nozzle and mounting therefor, a maximum pressure control valve attached at a source of fluid under pressure, and connecting means between said valve and nozzle. The nozzle is provided with a self contained normally closed valve preferably operable upon pressure of the nozzle against the material to be removed. To save the nozzle and connecting means from the effects of excessive pressures, the control valve is arranged to close when an excess pressure arises in the nozzle or connection so that excessive pressure therein will be

avoided. The device is used by pressing the nozzle against the material to be removed to start a stream of water against such material, and then pressing the device forward into the resulting hole as fast as may be possible or desirable to continue the water flow.

In the embodiment shown in Figures 1 and 2, a nozzle holding block 7 is provided, having a nozzle 8 slidably mounted in a bore 9 provided in the nozzle block. The nozzle 8 is tubular in form, is provided at its upper end with a disc valve 11, and has transverse perforations 12 formed in its upper portion adjacent the end. The valve 11 is arranged to seat on the upper end 14 of the block 7, the latter being provided with a cylindrical recess 16 opening in said end and surrounding the adjacent nozzle portion. It will now be noted that when the valve 11 is unseated, liquid may flow through the recess 16 and perforations 12 to the nozzle, whereas, when the valve 11 is seated the flow of liquid is prevented. Actuation of the valve is arranged to be effected upon relative movement of the block 7 and nozzle 8, the valve being normally held closed by the water pressure. Movement to open the valve is here shown provided for by means of pressure of the nozzle end 17 against the material to be removed, so that the flow of water is thus controllable at the point of application.

45 Connection of the nozzle and block to a source of liquid under pressure is here shown affected by means of an elbow member 18 arranged to receive the block 7 at one end and to be attached at the other end to a flexible hose 19 by means of the hose coupling 21 of the usual type. The other end 22 of the hose 19 is arranged to be connected to a source of fluid such as the faucet 23 here shown. In order to prevent undue pressures being exerted in the hose and nozzle, an automatic pressure control mechanism 24 is preferably inserted between the hose end 22 and faucet 23. In the present embodiment, the pressure control mechanism 24 comprises a valve 26 normally held unseated in the path of the liquid therethrough by means of a spring 27. 50 In case of stoppage of the flow through the nozzle 8 or any other cause for the creation of an excess pressure on the valve 26, the valve 26 will close and thus protect the hose and nozzle from the possibly destructive effects of such pressure.

55 It will be noted that the nozzle end 17 is

preferably cut bevelled, so that water escaping therethrough may be less easily blocked by contact of the end with the material to be removed. To limit the relative movement 5 of the nozzle and block, cooperating stops 25 and 25' are provided in the lower end of the block and on the outer portion of the nozzle respectively. By forming the stops 25 and 25' as an annular seat and valve re- 10 spectively, leakage of liquid along the nozzle when the valve is wide open is positively prevented.

In the embodiment of Figure 3, the nozzle 31 is held in threaded engagement with the 15 nozzle block 32, the latter being in the form of an elbow, and a piece of pipe 33 is connected between the block 32 and hose coupling 34. Control of fluid flow through the nozzle is here shown provided for by means of a 20 valve 35 seated in and adjacent the end of the nozzle 31 and having a stem 36 normally extending forwardly thereof and of the nozzle. Unseating of the valve 35 may be readily effected by pressing the stem 36 against 25 the material to be removed.

In the embodiment of Figure 4, the nozzle block 41 is provided with a valve 42 arranged to be normally held closed by means of the 30 water pressure. The valve 42 is adapted to be opened by manual pressure directed against the valve stem 43 of the valve, the latter being provided with a suitable gland 44 and packing 45 where it emerges from the block 41. As in the previously described em- 35 bodiments, a portion of the device is arranged to extend transversely of the nozzle, thus facilitating the handling of the device and the exertion of a pressure longitudinal- 40 ly of the nozzle during the boring process. As here shown, the portion of the block 41 containing the valve extends transversely of the nozzle and is arranged to receive the hose coupling 46 at its end.

In the embodiment of Figure 5, a straight 45 nozzle block 51 is threaded to receive a nozzle 52 at one end and a pipe 53 at the other end in colinear relation with the nozzle. A valve 54 is arranged to seat on the inner end of the nozzle and is provided with a 50 stem 55 extending through and protruding from the nozzle when the valve is seated. To insure proper seating of the valve, guide vanes 56 are provided on the outer end of the valve stem. This embodiment, it will be 55 noted, is particularly adapted to be attached to the end of a pipe or hose for movement into and through a boring. It will be noted that the nozzle 52 lies entirely within the block 51.

60 The construction of the embodiment shown in Figure 6 is similar to that shown in Fig-

ure 5, except that the nozzle 62 and valve stem 63 thereof are longer and extend a considerable distance forwardly of the block.

The device here described, it will now be 65 evident, should prove to be of particular value in post hole and other digging where softening of the ground by moisture is so frequently necessary. Not only will the earth surrounding the nozzle be moistened, 70 but a hole will actually be formed which may be used as dug or enlarged, as may be desired.

While we have described the device of our invention as being adapted for boring holes, 75 it is obvious that the device may be used for injecting a solution into the ground.

We claim:

1. A hydraulic boring device comprising a 80 nozzle having a passage therethrough, means connecting said passage with a source of liquid under pressure, a valve interposed in said nozzle passage and arranged to be normally held closed by said pressure, and means associated with said nozzle engageable with the material to be removed to effect the opening of said valve during the engagement of said means with said material.

2. A hydraulic boring device comprising 85 a nozzle block arranged to be attached to a source of liquid under pressure, a nozzle mounted in and extending from said block and having a fluid passage therethrough, and means in said passage operable in accordance with the contactual relation of said nozzle to the material to be removed for controlling the flow of liquid through the nozzle against said material.

3. A hydraulic boring device arranged 100 for attachment to a source of fluid, comprising a nozzle having a fluid passage extending therethrough, a valve arranged to normally close said passage, and means arranged at the discharge end of said nozzle whereby said valve may be opened by the application of pressure against said means.

4. A hydraulic boring device comprising 105 a nozzle having a fluid passage arranged therein, a valve operatively disposed in said nozzle passage and arranged to normally close said passage, and means on said nozzle whereby said valve may be automatically opened by and upon an appropriate projection of said means against the material to be 110 removed.

In testimony whereof, we have hereunto set our hands at Oakland, California, this 16th day of October, 1924.

WESLEY S. MALLOY.
